(57) CLAIM

The ornamental design for a shoe, as shown and described.

DESCRIPTION

FIG. 1 is a side view of a shoe showing my new design; FIG. 2 is a front perspective view thereof; FIG. 3 is a front view thereof; FIG. 4 is an opposite side front perspective view thereof; and, FIG. 5 is an opposite side view thereof.

The broken line within the shaded area shown in FIGS. 1-3 represents a seam which forms no part of the claimed design. The broken line showing of the top surfaces of the stripe elements forms no part of the claimed design. The broken lines immediately adjacent to and surrounding the shaded area define the peripheral bounds of the claimed design and form no part thereof. The broken lines depicting the remainder of the shoe form no part of the claimed design.

1 Claim, 5 Drawing Sheets
